Des. 236,686
Patented Sept. 9, 1975

236,686

COMBINED BOTTLE AND DISPENSING CAP

Herbert Ashley Atkins, Maidenhead, England, assignor to
Beecham Group Limited, Brentford, England

Filed Aug. 15, 1972, Ser. No. 281,008

Claims priority, application Great Britain Feb. 21, 1972

Term of patent 14 years

Int. Cl. D9—01

U.S. Cl. D9—130

FIG. 1

FIG. 2

FIG. 3

FIG. 4

FIG. 5

FIG. 1 is a perspective view of a combined bottle and cap therefor showing my new design;

FIG. 2 is a top plan view;

FIG. 3 is a bottom plan view;

FIG. 4 is a side elevational view; and

FIG. 5 is an end elevational view thereof.

I claim:

The ornamental design for a combined bottle and dispensing cap, as shown.
